4" Inventor:
Robert J. Wilson
by his Attorney: ~

Albert C. Tanner.

UNITED STATES PATENT OFFICE.

ROBERT J. WILSON, OF NEW YORK, N. Y.

DISINFECTING APPARATUS.

SPECIFICATION forming part of Letters Patent No. 761,122, dated May 31, 1904.

Application filed February 11, 1903. Serial No. 142,849. (No model.)

To all whom it may concern:

Be it known that I, ROBERT J. WILSON, a citizen of the United States, and a resident of New York, Manhattan borough, in the county 5 and State of New York, have invented certain new and useful Improvements in Disinfecting Apparatus, which improvements are fully set forth in the following specification.

This invention relates to improvements in 10 contrivances of that class extensively availed of for the purpose of generating and distributing a gaseous disinfectant, such contrivances being commonly known as "disinfecting" apparatus.

15 The object of this invention is to provide a disinfecting apparatus which shall be simple and inexpensive as regards construction, durable, efficient, and reliable in operation, convenient in its application to practical purposes, 20 which shall embody features of construction whereby steam or a similar heating medium may be employed in connection therewith, and which shall possess certain well-defined advantages over prior analogous structures.

25 The invention consists in the novel disposition and relative arrangement of the various parts thereof whereby the attainment of the foregoing object is rendered practicable, in certain combinations, and in certain details of 30 construction, all of which will be specifically referred to hereinafter and set forth in the appended claim.

The invention is clearly illustrated in the accompanying drawings, wherein similar reference-numerals denote corresponding parts throughout the several views, and as to said drawings—

Figure 1 is a plan view of a disinfecting apparatus constructed in accordance with my invention. Fig. 2 is a side elevation of same. Fig. 3 is a central vertical section along the line *a a* of Fig. 1.

In a general sense my invention comprises a jacketed generating-tank having an inlet- 45 port and a delivery-spout, a charger adjacent to said tank and communicating therewith by way of said inlet-port, and means for controlling the delivery of the contents of said charger to and into said tank, the jacket conjoined with 50 said tank being adapted to permit the use of

steam or the like for heating said tank and its contents, the whole comprising a compact portable convenient structure.

Having reference to the accompanying drawings, I make use of a generating-tank which 55 ordinarily comprises a main portion 2, bottom portion 2', and cover 2". Bottom 2' may be formed integral with the main portion 2, as in the process of casting, may be brazed thereto, or may have a threaded engagement therewith, as illustrated in the drawings. To facilitate the work of assembling the various parts of the device and the gaining of access to the interior of the generating-tank, cover 2" should be removably conjoined with the main portion 60 2, and to this end I have shown said cover as having a threaded engagement with said main portion.

Generating-tank 2 is cylindrical in cross-section and is provided with exterior threads at 70 its upper portion, such threads serving, primarily, a purpose to be hereinafter explained, and, secondarily, to receive the cover 2".

3 denotes an uncontrolled delivery-spout for the generating-tank of my improved apparatus, and in connection with such generating-tank I further make use of a jacket, here shown as comprising a main portion 3', a bottom portion 3", and a cap 4. While the bottom 3" and the cap 4 are shown in the accompanying 75 drawings as having, respectively, a threaded engagement with the main portion 3', one of these parts, and by preference the bottom 3", may be formed integral with the main portion 3' or brazed thereto, it being essential that 80 only one of such parts, and by preference the cap 4, be removably conjoined with the main portion 3' in order to insure convenience in assembling the parts and in gaining access to the interior of said jacket when desired. 90

4' is a valve-controlled inlet for said jacket, and 4" a valve-controlled exhaust therefor.

Primarily the cap 4, which has an enlarged threaded central opening, is screwed onto the main portion 2 and so that the upper terminus 95 of the latter projects somewhat beyond said cap. Then the depending portion of the generating-tank is let into the jacket aforesaid, and thereafter the cap 4 is screwed onto the main portion of said jacket at the top thereof, 100

said jacket being cylindrical in cross-section, exteriorly threaded at its upper portion, and said cover being shaped and threaded accordingly, all as clearly indicated in the drawings.

5 When the parts are thus assembled, a space 5, surrounding the major portion of the generating-tank, is formed for the reception of the heating medium, as steam, hot air, or the like, such heating medium being admitted to 10 said space by way of the inlet 4. Cover 2" is then screwed onto the upper extremity of that portion of the generating-tank which projects beyond the cap 4. I further make use of a charger 5', adapted to deliver its contents 15 under control to and into the generating-tank of my improved apparatus. This charger is provided with a delivery-neck 5", which engages the cover 2" at the inlet-port 6, formed in the latter, and is controlled by any appropriate device, as the valve 6'. Charger 5' is 20 provided with a cover 6", having a filling-nozzle 7 formed integral therewith by preference, and the latter (said nozzle) having a funnel 7' arranged in conjunction therewith to 25 facilitate the operation of filling said charger.

The nozzle 7 is controlled for venting purposes by any appropriate device, as the valve 7".

I purpose to employ, in connection with my 30 improved apparatus, an element or commodity adapted to yield a disinfecting gas or vapor under the application of heat, such element being first introduced into the charger 5' and thereafter under control as to volume or 35 quantity through proper manipulation of the valves 6' 7" into the generating-tank of the apparatus, wherein upon such element being subjected to the action of heat, as by introducing into the space 5 steam, hot air, or the like, a disinfecting gas or vapor is generated, 40 which gas or vapor moves outwardly from said tank by way of the uncontrolled delivery-spout 3 for final distribution. In this con-

nection the product known as "formalin" has been found to serve exceptionally well the 45 purposes of the gas or vapor generating element aforesigned, the same yielding under the application of heat a gas of special merit as a disinfecting agent and known as "formaldehyde."

50

While my improved apparatus is well adapted for the handling of gas or vapor generating elements quite generally for the generating of a gas or vapor therefrom, it is specially advantageous as a device for the handling of 55 formalin and the generating therefrom of formaldehyde gas.

It will be observed that my improved apparatus may be modified to some extent without materially departing from the spirit and 60 principle of my invention.

Having thus described my invention, what I claim, and desire to secure by Letters Patent, is—

A portable disinfecting apparatus comprising a heating-jacket having inlet and outlet ports; a movable annular cap for said jacket, having a central screw-threaded opening therein; a vapor-generating chamber projecting through said opening, engaging with said 70 screw-threads, and partly inclosed in said jacket; a removable cover fitting over the end of said vaporizing-chamber; a vapor-delivery pipe projecting through the cover, and into said vaporizing-chamber; a liquid-charging 75 chamber above the vaporizing-chamber; a valve for regulating the admission of liquid from said charging-chamber to the vaporizing-chamber; and a valve for shutting off the inlet to the charging-chamber when the same is 80 charged, all substantially as described.

ROBERT J. WILSON.
